ATTORNEYS

UNITED STATES PATENT OFFICE.

JOHN LEVI KINIKIN, OF GARDEN CITY, KANSAS.

SELF-ADJUSTING CURTAIN-DRAPE.

1,344,233.

Specification of Letters Patent. Patented June 22, 1920.

Application filed December 23, 1919. Serial No. 346,914.

To all whom it may concern:

Be it known that I, JOHN L. KINIKIN, a citizen of the United States, residing at Garden City, in the county of Finney and 5 State of Kansas, have invented a new and useful Self-Adjusting Curtain-Draper, of which the following is a specification.

This invention has reference to means adapted for being secured to window or 10 door casings for draping curtains, portières and the like and primarily the said invention has for its purpose to provide a device or means of the character stated of a very simple nature, that can be economically constructed and that is capable of being conveniently and securely applied to a window or door casing without the necessity of using screws and other securing devices and which is self-adjustable whereby it can be 15 20 instantly fitted onto different widths of casings.

A further object of my invention is to provide a curtain draper, of the kind stated having the parts so designed and co-operatively arranged whereby it may be so applied and adjusted along the casing without contact with the curtain or portière and with which the curtain or portière may be 25 30 readily engaged and held from being disconnected therefrom under the ordinary hanging of the drapery.

With other objects in view and which will be apparent, my invention embodies, in a curtain draper, the peculiar features of construction and novel arrangement of parts 35 fully set out in the following detailed description, specifically stated in the appended claims and illustrated in the accompanying drawing, in which:

40 Figure 1 is a perspective view of a portion of a window and its casing and my improved curtain draping device shown as applied for use.

Fig. 2 is a plan view thereof, the same being shown applied to a window casing, the latter being shown in horizontal section.

Fig. 3 is a perspective view of the device, the manner of draping the curtain being indicated in this view.

50 Fig. 4 is a plan view of the two resilient band portions in blank form and the spring device hereinafter more specifically referred to.

In the practical arrangement thereof, my 55 improved curtain draping device consists of a body composed of two bands or strips

1, 1, of resilient metal and of unequal length, as is best shown in Fig. 4.

One of the said metal strips, the shorter one, has one end 10 bent back upon itself to 60 lie flatwise against the main portion 11, whereby to form a loop 2, the purpose of which will presently appear.

The outer end of the bent back portion 10 is bent at right angles to the said portion to form a clamping member 3 adapted for fitting over and engaging one edge, the inner one 40, of the window casing 4, when the parts are assembled for use, as shown in 65 Fig. 2.

The inner or free end of the shorter member 1 is doubled back into a U-shaped arm 5, the free end of which terminates in substantially transverse alinement with the vertical loop 2.

The larger one of the strips 1 has one end bent back upon itself to form a vertical loop 20 and has the extremity of the bent back portion bent inwardly at right angles to constitute a clamping member 30, which, 80 when the parts are assembled as in Figs. 1 and 2, extends over and engages the other edge 41 of the window casing, see Fig. 2.

The outer end of the longer strip 1 is also bent to form a U-shaped arm 50 and the 85 said arm 50 is of a length sufficient to extend over and engage with the free end of the shorter U-shaped arm 5, its extremity being rounded outwardly, as at 52, to facilitate entering the curtain or other drapery 90 between the two opposing arms 5 and 50, which together form an inclosure within which the curtain may be draped, as is clearly indicated in Fig. 1.

6 designates a stout coil spring, the opposite ends of which are each attached to a triangular wire clip 7, which latter, when assembling the parts for use, may be readily slipped between the looped ends of their 95 respectively engaged arms 5 and 50 and fitted within the loops 2 and 20 of the said arms, it being apparent, by reference to the drawings, that by connecting the spring 6 to the inner ends of the curtain container arms 5 and 50, as stated and shown, the 100 105 clamps 3 and 30 may be readily adjusted to suit window casings of different widths and, when slipped over the opposite edges of the casings, the clamps 3 and 30 will securely sustain the device in place, it being understood that when necessary to adjust the draper device up or down the casing to the 110

desired position for holding the draper curtain portions, it is only necessary to apply outward pressure to the two opposing arms 5 and 50, in the direction of the arrows on 5 Fig. 2, to sufficiently release the clamps 3 and 30 that they may be freely slid up or down the casing edges, as desired.

From the foregoing description taken in connection with the accompanying drawing, 10 the construction, the manner of use and the advantages of my invention will be readily understood.

The body of the device consists essentially of two flat strips of resilient metal capable 15 of being bent up to the desired shape, which provides for manufacturing the device at a very small cost, and, since no screws or like fastening means are needed for holding the device in place on the window casing, 20 scratching or otherwise marring the casing is avoided.

By forming the device in the shape of a container in which the folds of the draped curtain may be easily inserted and held, 25 danger of the curtain becoming soiled by contact with the screen or drawn through the window opening in also overcome.

What I claim is:

1. A curtain draper composed of two opposing and overlapping resilient U-shaped members, one of the ends of each of said members constituting a clamp portion for engagement with the edge of a window casing, a tension device for drawing the said 30

ends together, whereby the clamp portions 35 are caused to grip the opposite edges of the window casing.

2. A curtain draper composed of two resilient members bent into U-shape, one end of each of the U-shaped members being bent 40 back upon itself, whereby to constitute a loop at the bend of the said member, the extremities of the said bent back members being projected at right angles to the body of the said members, whereby to constitute 45 clamps for engaging a window casing edge, a spring interposed between the looped ends of the resilient members, a link connected to each end of the spring, the said ends being adapted for slipping between the bent back or lapped portions of the resilient members, whereby to engage with the looped ends thereof.

3. A curtain draper composed of two opposing resilient U-shaped members, one of 55 the ends of each of said members being bent to constitute a clamp portion for engagement with the edge of a window casing, a tension device for drawing the said ends together, whereby the clamp portions are 60 caused to grip the opposite edges of the window casing, one of the said resilient members being of greater length than the other and held overlapped and closely against the outer or free end of the other resilient 65 member.

JOHN LEVI KINIKIN.
